CLAIM

The ornamental design for an injector device for a syringe, as shown and described.

DESCRIPTION

FIG. 1 is a perspective view from the bottom and front sides of an injector device for a syringe.

FIG. 2 is a perspective view from the top and front sides thereof.

FIG. 3 is a rear elevation view thereof.

FIG. 4 is a left elevation view thereof.

FIG. 5 is a front elevation view thereof.

FIG. 6 is a right elevation view thereof.

FIG. 7 is a top elevation view thereof.

FIG. 8 is a bottom elevation view thereof.

FIG. 9 is a perspective view from the bottom and front sides of the injector device of FIG. 1 showing the cap exploded from the remainder of the device; and,

FIG. 10 is a perspective view from the top and front sides of the injector device of FIG. 1 showing the cap exploded from the remainder of the device.

The broken lines showing portions of an injector device for syringe are included for the purpose of illustrating environmental structure and form no part of the claimed design.

1 Claim, 10 Drawing Sheets
